(57) **CLAIM**

The ornamental design for a guide for suturing needle, as shown and described.

DESCRIPTION

FIG. 1 is a front perspective view of a guide for suturing needle in accordance with the present invention;

FIG. 2 is a back perspective view of the guide for suturing needle of FIG. 1;

FIG. 3 is a front view of the guide for suturing needle of FIGS. 1 and 2;

FIG. 4 is a side view of the guide for suturing needle of FIGS. 1-3, the opposite side view being a mirror image thereof; and,

FIG. 5 is an end view of the guide for suturing needle of FIGS. 1-4.

The broken lines are directed to environment and are for illustrative purposes only; the broken lines form no part of the claimed design.
